BOWED EXPANDER ROLL

Charles W. Shute, Boston, Mass., assignor to
 Frederick T. Walsh, doing business as Thomas
 Leyland Machinery Company, Boston, Mass.

Application February 1, 1937, Serial No. 123,438

11 Claims. (Cl. 26—63)

This invention is an improvement in bowed expanders of the Mycock type for cloth and other continuous web material, and in particular relates to the bobbins which are mounted on a stationary curved shaft, to form an articulated curved roll usually rotated by drawing the web material over it, the outward component of travel of the surfaces of the bobbins as they rotate in planes oblique to the travel of the material being utilized to open and expand the sheet of web material in both directions away from its middle line.

The bobbins comprising each roll are interlocked or clutched together, or else fixed tightly in a common rubber tube or covering, to ensure their turning in unison, so as to attain uniform spreading action across the width of the material and also to avoid excessive wear between the bobbins or between the bobbins and the cover. Hitherto these clutches have been unsuited for use in rubber covered rolls, and when used in bare rolls have always been of the full diameter of the bobbins, being made as by forming a rectangular recess at two or more spaced points in the cylindrical cloth engaging surface at the ends of the bobbins, so that the projections thus formed on the end of each bobbin will fit into the corresponding recesses made in the cloth-engaging surface at the end of the adjacent bobbin.

In use, these expander rolls are subjected to very considerable strains and vibrations, with the result that the co-engaging driving shoulders on the clutches thus formed on adjacent bobbins of these bars, all-metallic expander rolls pound burrs onto the upper edges of the clutches. These burrs prick the cloth as drawn around the rolls, making fine perforations both by spreading the yarns and by cutting and breaking the yarns themselves, and otherwise damaging the quality of the fabric.

A further drawback is that on starched goods, the edges of the driving shoulders of the clutches press into and leave objectionable marks on the surface of the fabric. In addition, the exposed spaces in the cloth-engaging surface necessarily occurring between each dog and its recess in this outside type of clutch collect lint and starch and water, and these after accumulation escape onto the cloth, to spot and mark the surface thereof. Additionally, the respective dogs of adjacent bobbins in this outside type of clutch strive to pull the same longitudinal elements or warps of the cloth simultaneously in opposite directions at closely spaced intervals in the length of the cloth

in the zone where the cloth overlaps these divergently traveling surfaces of the two bobbins. This is objectionable as it tends to pull the warps out of their intended straight-line extent in the fabric. As the bobbins are commonly made with annular ridges of saw-tooth profile over the entire cloth-engaging surface, with a rake toward the ends of the roll, to enhance the frictional grip and hence the spreading action of the rolls on the fabric, the warps which are sunk by tension into the peripheral teeth of two adjacent clutch dogs of a pair of bobbins are subjected to a wrenching and shearing action where the driving faces of the clutch dogs meet, which limits the depth and sharpness of the teeth to somewhat less than might otherwise be desired for most effective expanding, in order to avoid too harsh and distorting action on the warps.

Further, there is a tendency to pinch the cloth between the ends of the dogs of this type and the bottoms of the corresponding recesses in the adjacent bobbin. Also, this type of outside clutch permits chewed-up fragments of the felt grease-retaining collar, used inside the bobbins, to escape and stain the cloth.

To remedy these shortcomings in the standard Mycock type of bare metallic expander rolls, and to offer advantages likewise obtainable in the case of rubber covered rolls, my invention comprises the provision of improved bowed expander bobbins having the devices which clutch adjacent bobbins together to rotate in unison disposed wholly below or within the web-engaging surfaces of the bobbins, or within the corresponding peripheral surfaces which engage the interior of the rubber cover in the case of covered rolls. In its preferred form, the cylindrical or full-diameter cloth- or cover-engaging surface of the bobbin contains no recess cut in its ends nor protrusions from such ends. Instead, the recesses and projections are formed on and in the ends of each bobbin at a lesser radius than the cylindrical or peripheral surface of the bobbin, so that when put together the clutches are wholly inside the surface of the roll and shielded thereby from all contact with the cloth. Thus any burring which occurs on the clutch dogs cannot injure the cloth, no marking, shearing effects, or distortion of the warps can arise at the driving shoulders of the clutches, there are no open recesses to collect lint, starch, and water, ground-up greasy fragments from the felt washer are impeded in their escape, and the annular teeth can be made as sharp as desired, and there is

no occasion to pinch the cloth at the ends of the dogs.

Other aims of the invention, and their resulting advantages and their methods of attainment 5 are as will be made plain herein.

An illustrative embodiment of the invention is shown in the accompanying drawing, in which—

Fig. 1 shows a portion of the curved shaft at mid-width of a bare-roll bowed expander, with 10 two of the improved bobbins thereon and shown in section, illustrating the manner of their inter-engagement, the curve of the shaft being exaggerated.

Fig. 2 is a side view of one of the improved 15 bobbins, partly broken away.

Figs. 3 and 4 are end elevations of opposite ends of the bobbin of Fig. 2.

The novel bobbin comprising my improved bowed expander roll shown in Figs. 2, 3 and 4 20 has as usual in the case of bare expander rolls a working surface of generally cylindrical shape, equipped with sharp annular ridges or teeth 1 having a rake or slant all in one direction. This cylindrical surface extends for the full length 25 of the entire surface of the bobbin which engages the cloth, without any projections or recesses in its unbroken terminal peripheral edges or rims at either end. At locations wholly below the ridged cloth-engaging surface there are 30 formed on the ends of each bobbin projecting integral clutch fingers or dogs 3, of segmental shape and concentric with the axis of the bobbin, and having their outside radius considerably less than the radius of the ridged working surface 35 of the bobbin. These dogs 3 may be of any suitable or desired number and extent in a direction around the axis, preferably having an extent equal to the spaces or intervals left between the several dogs and thus being equally 40 spaced about the circuit of each end. The end of each bobbin is recessed as indicated at 5 between each two projecting dogs 3, so that when put together on the curved shaft 7 as in Fig. 1 practically the entire length of each dog 45 3 is received within and shielded by the corresponding recess 5 in the end of the adjacent bobbin. The material of the end is also removed just inside the dogs 3 to the same depth as the dog-receiving recesses 5, to form an annular space 50 8 extending all the way around the circuit of the end, in which cylindrical felt collars 9 are located, and to leave a hub 11 in which is fixed a bushing 13 to bear against the surface of the shaft. The felt collar 9 seats simultaneously in 55 the bottom of the space 8 of both bobbins when in working relation, to prevent the escape of dirt and lubricant outwardly from the bearing surfaces.

The parts are fitted so that the opposing rims 60 15 of the adjacent bobbins will not be allowed to come into contact with or approach very closely to each other at the concave side of the shaft, or at any point where engaged by the cloth, in the course of their rotation so that the 65 fabric will not be pinched between the opposite rims. Preferably, as shown in Figs. 1 and 2, this is accomplished through extending the hubs 11 axially outward far enough to bring the flanges of the bushings 13 into bearing engagement with 70 each other before the rims 15 can engage each other. This may also be attained by making the mutually interlocking dogs 3 and their corresponding recesses of such length and depth that the dogs bottom in the recesses and hold the 75 rims 15 apart at the concave side of the roll.

The dogs 3 have their exterior surfaces tapered slightly, to facilitate their entry into the recesses of each adjacent bobbin, and to provide for the disalignment of the axes of the bobbins; similarly, the driving shoulders 17 of each dog are given a slight and equal taper toward each other.

Application of the invention's principle of putting the clutches below and within the peripheral surface, to the making of rubber covered rolls is accomplished in obvious and analogous 10 manner. The teeth 1 are omitted from the bobbin, which may have either a smooth cylindrical surface to engage the interior of the rubber covering or any of the known polygonal, ridged, or ribbed surfaces designed to hold the cover against 15 rotation with respect to the bobbins. As is obvious, the cover is relieved of the wrenching strains of having to drive individual lagging bobbins whose bearings run dry or bind on the curved shaft, since interlocking bobbins may thus be 20 used inside the cover without the clutches pinching and chewing the inside of the cover and wedging the torn-off bits of rubber in the clutch recesses to make the roll turn hard; the rubber thus chewed up is not present to collect in 25 bunches between the cover and the bobbin, to form lumps distorting the exterior surface of the roll and straining the covering, and the covering does not so quickly swell and relax its grip and thereafter wrinkle and become useless 30 since there are no individual lagging bobbins to move relatively to the interior surface of the covering and start this destructive process. When thus relieved of these destroying forces, increased useful life is given to these relatively expensive 35 rubber covers.

While I have illustrated and described a certain form in which the invention may be embodied, I am aware that many modifications may be made therein by any person skilled in the art, 40 without departing from the scope of the invention as expressed in the claims. Therefore, I do not wish to be limited to the particular form shown, or to the details of construction thereof, but

What I do claim is:

1. In a bowed cloth expander, in combination, a curved shaft, bobbins rotatably mounted thereon and revolved by the traveling cloth, and means clutching adjacent bobbins together to rotate in 50 unison, said clutching means being constructed to keep from contact with each other all portions of such adjacent bobbins which are in contact with the cloth whereby the cloth is prevented from being pinched between adjacent bobbins. 55

2. A bobbin for a bowed cloth expander having an unbroken circular periphery at the end of its cloth-engaging surface, and means lying wholly below said surface engaging an adjacent bobbin to compel the two bobbins to rotate in 60 unison, and to maintain the opposing ends of the respective cloth-engaging surfaces of the two bobbins in spaced relation to avoid pinching the cloth between adjacent bobbins.

3. In a bowed expander for web materials, in 65 combination, a curved shaft, and web-engaging bobbins thereon each having at each end integral mutually interlocking segmental projections extending axially beyond the end of its web-engaging surface compelling adjacent bobbins to 70 turn in unison, such projections being covered by the web-engaging surface of the adjacent bobbin where they extend within the length of such bobbin.

4. In a bowed expander for web materials, in 75

combination, a curved shaft, and expander bob-
